FOREIGN PATENT DOCUMENTS

CA 2286959 A1 1/2000

Primary Examiner — Jennifer L Watkins(74) *Attorney, Agent, or Firm* — Erickson Kernell IP,
LLC; Ginnie C. Derousseau(57) **CLAIM**

The ornamental design for a thumb brace, as shown and described.

DESCRIPTION

FIG. 1 is a front perspective view of the thumb brace in accordance with the present invention;

FIG. 2 is a rear perspective view of the thumb brace of FIG. 1;

FIG. 3 is a front elevation view of the thumb brace of FIG. 1;

FIG. 4 is a rear elevation view of the thumb brace of FIG. 1;

FIG. 5 is a first side view of the thumb brace of FIG. 1;

FIG. 6 is an opposite side view of the thumb brace of FIG. 1;

FIG. 7 is a top view of the thumb brace of FIG. 1;

FIG. 8 is a bottom view of the thumb brace of FIG. 1;

FIG. 9 is a front view of the thumb brace of FIG. 1 in an open, released position; and,

FIG. 10 is a front view of the body of the thumb brace of FIG. 1 showing the brace strap removed therefrom.

The broken lines on the thumb brace are for the purpose of illustrating stitching and form no part of the claimed design.

1 Claim, 6 Drawing Sheets---
